UNITED STATES PATENT OFFICE.

ADOLPH WOLFGANG, OF DETROIT, MICHIGAN, ASSIGNOR TO DETROIT CAP MANUFACTURING CO., OF SAME PLACE.

DESIGN FOR A CAP.

SPECIFICATION forming part of Design No. 26,451, dated December 29, 1896.

Application filed October 27, 1896. Serial No. 610,229. Term of patent 3½ years.

To all whom it may concern:

Be it known that I, ADOLPH WOLFGANG, a citizen of the United States, residing at Detroit, in the county of Wayne and State of Michigan, have invented and produced a new and original Design for a Cap, of which the following is a specification, reference being had therein to the accompanying drawings, in which—

10 Figure 1 is a side elevation of a cap embodying my new design. Fig. 2 is a plan view thereof, and Fig. 3 is another side elevation of the same cap with the intermediate section as in a state of collapse.

15 A is the vizor.

B is a base-section, the upper edge of which lies in a plane which slopes toward the front.

C is an intermediate section which gradually expands outwardly all around from the base up, and D is the crown, which is formed slightly convex or pileate and is contrasted by radial bars E and intermediate triangular

sections F between the bars. An ornamental knob or button G is generally placed in the center of the crown.

25 The design is principally characterized by the base-section B, umbrella-shaped appearance of the body, and by the configuration of the confluent portion or rim formed by the junction of the intermediate section with the crown, which presents a marked corner H at the base of each bar, thereby giving to the rim the umbonated contour more clearly shown in Fig. 2.

30 What I claim as my invention is—

35 The design for a cap as herein described and shown.

In testimony whereof I affix my signature in presence of two witnesses.

ADOLPH WOLFGANG.
